(57) **CLAIM**

We claim the ornamental design for a safety handle, as shown and described.

DESCRIPTION

FIG. 1 is a top plan view of a safety handle according to the present design;

FIG. 2 is a bottom plan view thereof;

FIG. 3 is a top perspective view thereof;

FIG. 4 is a bottom perspective view thereof;

FIG. 5 is a side elevation view thereof;

FIG. 6 is an opposite side elevation view thereof;

FIG. 7 is a front elevation view thereof;

FIG. 8 is a back elevation view thereof; and,

FIG. 9 is a cross-sectional view thereof taken along lines 9-9 shown in FIG. 1.

The dash-dot-dash lines shown represent the plane upon which the cross-sectional view is taken and form no part of the claimed design.

1 Claim, 5 Drawing Sheets
